DESIGN FOR A TABLE UTENSIL REST

Frank E. A. Larson, Washington, D. C.

Application October 16, 1936, Serial No. 65,330

Term of patent 3½ years

To all whom it may concern:

Be it known that I, Frank E. A. Larson, a citizen of the United States, residing in Washington, in the District of Columbia, have invented a new, original, and ornamental Design for a Table Utensil Rest, of which the following is a specification, reference being had to the accompanying drawing, forming a part thereof.

Figure 1 is a side elevational view of a table utensil rest, showing my new design.

Figure 2 is a top plan view of the same, and Figure 3 is an enlarged sectional view taken along line 3—3 of Figure 2.

I claim:

The ornamental design for a table utensil rest, as shown.

FRANK E. A. LARSON.
